JOSEPH F. DAILY, OF ST. LOUIS, MISSOURI.

LINK FABRIC.

1,257,323.

Specification of Letters Patent. Patented Feb. 26, 1918.

Application filed October 29, 1917. Serial No. 199,058.

To all whom it may concern:

Be it known that I, JOSEPH F. DAILY, a citizen of the United States, residing at St. Louis, State of Missouri, have invented certain new and useful Improvements in Link Fabrics, of which the following is a full, clear, and exact description, reference being had to the accompanying drawings, forming a part hereof.

10 The present invention is directed to that class of wire fabrics known as the link fabric, a form used to a considerable extent for purposes of a bed-bottom or the resilient member on which the mattress and bedding 15 are supported. The invention has for its objects (1) to provide a fabric involving the use of a minimum quantity of wire, this result being attained by dispensing with the employment of twisted links; (2) to provide 20 a fabric having a maximum resilience and one which will readily yield and conform to the movements of the occupant of the bed; (3) to provide a fabric which shall afford a smooth surface of support for the mattress or 25 bedding; (4) to provide a fabric in which the links shall be effectively locked to one another; (5) to provide a fabric which shall contain a maximum number of joints on the 30 presence of which the resilience of the fabric depends; and (6) to provide a fabric possessing further and other advantages the nature of which will be fully apparent from the following detailed description in connection with the accompanying drawings in 35 which—

Figure 1 represents a plan of a portion of the improved fabric serving the purpose of a bed bottom; Fig. 2 is an enlarged vertical longitudinal section on the line 2—2 of Fig. 40 1; Fig. 3 is an enlarged vertical cross-section on the line 3—3 of Fig. 1; Fig. 4 is a top plan of one of the longitudinal units or pairs of links entering into the construction of the fabric; Fig. 5 is an enlarged cross-45 section on the line 5—5 of Fig. 4; Fig. 6 is a top plan of one of the links detached; Fig. 50 7 is a side elevation thereof; Fig. 8 is a bottom plan of a slightly modified construction of longitudinal unit; and Fig. 9 is a side view of Fig. 8.

Referring to the drawings, and for the present to Figs. 1 to 7 inclusive, 1 represents one of the end rails of a bed-bottom frame, said rail in the present instance being in the 55 form of an angle bar, and well understood in the art. Carried by the end rails are the

helical springs 2 to which the ends of the fabric are secured. The improved fabric comprises a series of pairs of longitudinally disposed wire links 3 terminating at one end 60 in hooks or loops 4 bent in the same direction, said direction being downward or away from the plane of the supporting surface of the fabric when serving as a bed bottom or equivalent support. The opposite ends of 65 the links 3 terminate in hooks or loops 5 disposed in horizontal planes or at right angles to the planes of disposition of the loops 4, the loop 5 of one link being bent in the opposite direction to the corresponding loop 70 of the opposite link, thereby forming right and left hooks, said hooks being superposed and their terminals crossing one another so as to form a closed composite loop or eye e. The hook or loop 5 which is on top when the 75 loops are superposed has its free end bent and extended downward or into a plane substantially parallel to the planes of disposition of the loops 4, said downwardly bent terminal forming a locking finger 5' which 80 engages the outer side of the loop or hook 5 of the opposite link 3, thereby preventing the eye e from opening, preventing as it does any accidental spreading of the intersecting terminals of the wires forming the loops 5 of 85 any pair of links. The purpose of bending downward the finger 5' from the upper loop 5 of the pair of superposed loops is to bring the point of the finger away from the plane of the supporting surface of the fabric to 90 prevent the point from tearing the bedding or mattress. The locking of the cross terminals of the superposed loops 5, 5, could of course be effected by turning the free end of the bottom loop upward; and while such 95 reversal would not fall outside the scope of the present invention, yet it would not be desirable in practice because of the danger of the point of the wire tearing the bedding, and otherwise presenting a rough supporting 100 surface.

The eye e of one pair of links receives the adjacent terminal hooks 4 of the next pair of links and so on throughout the series, the eyes e of the terminal pairs of links at one 105 end being coupled to the helical springs 2 secured to the end rail 1 at that end, and the loops 4 of the terminal pairs of links at the opposite end being coupled to the helical springs secured to the end rail (not shown) 110 at the opposite end of the bed. The disposition of the units or links 3, 3, in pairs

as described, with the loops 4 disposed in vertical planes and the loops 5 in horizontal planes but turned in opposite directions (right and left) relatively to one another, 5 causes the members of any pair of links to diverge from their points of anchor at the loops 4 toward their points of connection at the eye e with the loops 4 of the next succeeding pair of links as clearly shown in 10 Fig. 1 of the drawing. In other words, the converging terminals of one pair of links are coupled to the diverging terminals of the next pair and so on through the series.

The eyes e (which are necessarily closed 15 as a result of the crossing or intersection of the free ends of the superposed loops or hooks 5) are availed of to receive the terminal hooks or loops 6 of the cross or transverse links 7. The eyes e being closed, it follows that the hooks 6 of the cross-links can 20 not work out of the eyes to permit said links to slide along the links 3 and away from their assigned position. The cross-links are thus maintained in permanent transverse 25 alignment between the eyes e of successive pairs of links 3.

It will be observed that at each eye e there is a meeting or convergence of not less than six hooks, to wit—two hooks 4, 4, two 30 hooks 5, 5, and two hooks 6, 6, any one hook having free play over another hook of the series, this freedom of play between any two hooks forming a flexible joint which is ever free to yield to any movement of the body 35 of the occupant of the bed. The advantage of a large number of joints lies in the fact that the joints make the fabric extremely sensitive and yielding, making such a fabric most comfortable to lie on, and most desirable 40 for service as a bed bottom. In the present embodiment of my invention the use of two independent hooks or loops 5, 5, whereby there is formed what may be termed a two-part eye e (instead of a one- 45 part eye which could readily be formed by properly bending and looping a single wire length) serves to contribute to the plurality of joints or yielding connections in the region of each eye as already pointed out. 50 Each hook 5, 5, is free to yield independently of the other depending on the character of strain imposed thereon. A one-part eye could never be as sensitive as a two-part eye where each part is left free to yield independently of the other part as is the case 55 in the present construction. The number of strains imposed on the links 3, 7, and on their hooks, 4, 5, and 6, when the fabric is in service are indeed many, their character depending 60 on the movements of the bed occupant; and where the joints of the fabric are sensitive and freely yield to these movements, nothing more can be desired. The construction here shown and described constitutes 65 an ideal fabric and fulfills the several

objects and purposes for which the same was designed.

To provide a two-part eye such as e, it is not necessary to employ two separate strands or lengths of wire as shown in the figures 70 above referred to. Thus, in the modification in Figs. 8 and 9, I show a two-part eye e at the terminals of a single piece of bent wire 3', said eye being formed by the overlapping of the hooks 5, 5, the same as in the first 75 form described. Where a single wire length is employed however it necessitates the formation at the medial point of the wire, of a single integral hook 4' which forms one of the terminals of the resulting link or unit, 80 said hook 4' taking the place of the independent single hooks 4, 4, in the first form described. The modification just referred to (Figs. 8 and 9) however is not as desirable as the first form for the reason that it is more 85 expensive to make, and second, the substitution of one hook 4' formed by doubling the wire, for the two independent single hooks 4, 4, reduces the number of yielding joints in the region of the eye, thereby detracting 90 in a measure from the flexibility, elasticity and yielding qualities of the fabric.

The terms "longitudinal" and "transverse" as applied to the links or strands are merely relative, that is to say they are intended to bring out the fact that one series of links are disposed in one direction and another series in a direction transverse thereto. It does not necessarily follow however that the sheet of fabric has its greater 100 dimension in the longitudinal direction, for a fabric may have a width in excess of its length. In the present instance the term "longitudinal" is used in connection with the links 3 because the end of the fabric is secured to the end rail 1 of a bed-bottom frame, which end rail is transverse to the longitudinal side rails (not shown) to which the links 3 are parallel. The term "hook" herein must be interpreted broadly, contemplating as it does any loop be the same closed or open, or any equivalent formation by which the member provided with said hook may be coupled to another member. The fabric as constructed may be said to be 105 composed of a series of parallel rows of longitudinally disposed units, each unit comprising a pair of links or wires (3, or their equivalent) terminating in hooks by which one unit is hinged or jointed to a succeeding 110 unit, the hooks at one end pointing in one direction and being disposed at right angles to those at the opposite end which point in opposite directions and are superposed to form a closed eye, the hooks of one unit 115 pointing in the same direction being jointed to the eye of a succeeding unit, said eye in addition being engaged by the adjacent terminals of the transverse links on either 120 side thereof, whereby two pairs of longi- 125 130

tudinal links and two single transverse links meet at the eye terminal of one of the units aforesaid. The eyes being closed, the links 7 can not slip out of them, and hence the 5 permanent retention of these links in their proper position is assured. The transverse links are likewise disposed in parallel rows, preferably at right angles to the direction of the rows of the longitudinal units, though I 10 do not wish to be restricted specifically to a right angle. The hooks 6 of the transverse links are bent in the same direction (downward) as the hooks 4 of the links 3, the terminal links 7 of the series being connected 15 to the side bars 8 the ends of which are coupled to the springs 2 as well understood in the art.

It is within the scope of my invention to reverse the links in alternate longitudinal 20 rows, thus bringing the eyes *e* of the links of one row opposite the hooks 4 of the opposite links in the adjacent row; or any other arrangement of the rows may be utilized so long as they are composed of the units as 25 set forth above.

Having described my invention what I claim is:

1. In a fabric of the character described, a link unit comprising two wire links in 30 juxtaposed relation and terminating at one end in hook formations disposed in a given plane, the opposite ends of the links terminating in superposed hooks turned in opposite directions and crossing one another to form a closed eye, said eye being disposed in a plane transverse to the plane of disposition of the hooks at the opposite end of the unit.

2. In a fabric of the character described, 40 a series of parallel rows each composed of units jointed to one another, said units comprising independent links disposed in pairs terminating at corresponding ends in closed eyes and at the opposite ends in suitable 45 hooks, the planes of disposition of the hooks being transverse to the planes of disposition of the eyes, the hooked end of one unit coupling to the eye terminal of the next succeeding unit, and links disposed transversely 50 to the jointed units aforesaid and terminating at opposite ends in hooks engaging the eyes of the units.

3. A link fabric comprising a series of 55 parallel rows of longitudinally disposed units, each unit comprising a pair of links terminating at one end in hooks tending or

pointing in the same direction and disposed in a given plane, and at the opposite end in hooks pointing in opposite directions and disposed in planes transverse to the plane of 60 disposition of the first-mentioned hooks, the oppositely-pointing hooks being superposed to form closed eyes, the hooks of one unit tending in the same direction being coupled to the eye of a succeeding unit, and transversely disposed links terminating in hooks 65 engaging the eyes on either side thereof, the hooks of the transverse links being bent in the same direction as the hooks coupled to the eyes aforesaid. 70

4. A bed-bottom wire link fabric comprising a series of parallel rows of longitudinally disposed units each composed of a pair of links diverging in one direction, the converging ends terminating in downwardly 75 bent hooks, and the diverging ends terminating respectively in right and left horizontally disposed hooks in superposed relation and crossing one another at their free ends, the terminal of the upper hook being bent 80 downwardly to form a locking finger engaging the outer side of the bottom hook, thereby forming a closed eye, the eye of one unit being coupled to the downwardly projecting hooks of the next succeeding unit, and 85 transverse links terminating in downwardly turned hooks coupled to the eyes of the longitudinal units.

5. In a fabric of the character described, a link unit comprising two wire links diverging from one another and terminating at the converging end in a hook formation disposed in a given plane, the diverging ends terminating in superposed hooks turned in 90 opposite directions and crossing one another to form a closed eye, said eye being disposed in a plane transverse to the plane of disposition of the hook formation at the opposite end of the unit.

6. In a fabric of the character described, 100 a plurality of series of longitudinal and transverse link members jointed to one another, each joint being formed by a convergence of four independent longitudinal links disposed in pairs and two single transverse links, as set forth.

In testimony whereof I affix my signature, in presence of two witnesses.
